UNITED STATES PATENT OFFICE.

WILLIAM P. HAMMOND, OF PASSAIC, NEW JERSEY.

DESIGN FOR A MIRROR ATTACHMENT FOR AUTOMOBILES FOR SHOWING THE REAR TRAFFIC CONDITIONS.

45,379.

Specification for Design.

Patented Mar. 10, 1914.

Application filed November 20, 1913. Serial No. 802,162. Term of patent 7 years.

To all whom it may concern:

Be it known that I, WILLIAM P. HAMMOND, a citizen of the United States, residing at Passaic, in the county of Passaic and State of New Jersey, have invented a new, original, and ornamental Design for a Mirror Attachment for Automobiles for Showing the Rear Traffic Conditions, of which the following is a specification, reference being had to the accompanying drawings, forming a part thereof.

Referring to the annexed sheet of drawings, Figure 1, represents a front elevation of my design for a mirror attachment for automobiles for showing the rear traffic conditions, made in accordance with my invention. Fig. 2 is a rear view thereof, the shaded portion representing an opaque surface.

The mirror attachment, as illustrated, is considerably greater in length than it is in width and is positioned at or near the top of

the wind shield or the front part of the vehicle at a sufficient height to render to the driver an unobstructed vision of the road being traveled by the vehicle, the mirror attachment being of substantially the same width as the wind shield or other part of the vehicle by which it is carried or on which it is mounted.

I claim—

The ornamental design for a mirror attachment for automobiles for showing the rear traffic conditions as shown and described.

In witness whereof I have hereunto set my hand in the presence of two subscribing witnesses, this 19 day of Nov. 1913.

WILLIAM P. HAMMOND.

Witnesses:

P. FRANK SONNEK,
LILLIAN L. MALZER.
